UNITED STATES PATENT OFFICE.

FREDERIC H. MANCHESTER, OF PROVIDENCE, RHODE ISLAND.

INCANDESCENT LAMP.

SPECIFICATION forming part of Letters Patent No. 469,483, dated February 23, 1892.

Application filed November 4, 1891. Serial No. 410,821. (No model.)

To all whom it may concern:

Be it known that I, FREDERIC H. MANCHESTER, of the city of Providence, in the county of Providence and State of Rhode Island, have 5 invented certain new and useful Improvements in Incandescent Lamps; and I hereby declare that the following is a full, clear, and exact description of the same, reference being had to the accompanying drawings, forming 10 part of this specification.

This invention has reference more especially to improvements in the bases in which the glass bulbs of the lamps are permanently secured and which are adapted to be secured 15 in lamp-sockets having a central contact-post and a circumferential contact-plate.

The object of this invention is to produce a base for incandescent lamps which will be more durable than those heretofore manufactured and reduce the cost of the same. To attain these ends, I have invented a lamp-base provided with an insulating-plate formed of porcelain, together with certain novel features of construction and peculiar combination of parts, which will hereinafter be more particularly described, and pointed out in the claim.

Figure 1 represents the improved base secured to the bulb of an incandescent lamp. 30 Fig. 2 represents a top view of the base. Fig. 3 represents a vertical sectional view of the base, taken at a line *a b*, Fig. 2, showing the manner in which parts of the base are secured together and connected with the lamp-wires.

Similar numbers of reference designate corresponding parts throughout.

In the drawings, 5 indicates the shell of the base. This shell is spun up from sheet metal 40 and has the corrugations 6 pressed from the thickness of the metal and forming a screw-thread, by which the base and the bulb held therein are secured in the lamp-socket. The lip 7 is provided at the upper portion of this 45 shell and is bent over the thin edge of the insulating-plate 8 to secure the same to the shell. The insulating-plate 8 is formed of porcelain and is circular in shape, having a thin edge 9, over which the lip 7 of the shell 50 is bent, and a central boss 10, which is perforated vertically, the perforation extending through the thickness of the insulating-plate into the cavity 11 in the under side thereof.

A side perforation 12 is also formed through the thinner portion of the plate 8. The perforated cap 13 fits closely around the edges of the boss 10 and is secured in place by the tube 14, the flange 15 of which fits into the cavity 11, while the upper end extends through the perforation of the cap 13, over 60 the edges of which it is expanded, drawing the upper surface of this cap downward and forming a slight concaved recess. The lamp-wire 16 extends through the perforation 12 and is secured, preferably by solder, to the 65 cap 13, while the wire 17 is secured to the metal shell 5, these wires being connected to the filament of the lamp. When this base is secured to a screw-socket, the shell 5 is connected with the inner shell of the socket and 70 thence to one pole of the electric circuit, and the upper edge of the tube 14 is forced into contact with a pin or plate connected with the other pole of the electric circuit. The porcelain insulating-plate 8 can be made 75 smaller and less cumbersome than when made of wood and may be more securely fastened to the shell 5 by simply spinning the lip 7 over the thin edge of the plate, as this plate can be molded complete in shape, and with 80 the perforations formed therein the cost of manufacture is greatly reduced. At the same time an insulating-plate is formed which will not become loose from shrinkage and which will not retain sufficient moisture to occasion 85 a short circuit of the electric current.

Having thus described my invention, I claim as new and desire to secure by Letters Patent—

In an incandescent lamp, the combination, 90 with the base 5, having the corrugations 6 and lip 7, of the porcelain insulating-plate 8, secured within said lip and having a side perforation 12 and a central perforated boss 10, a metal cap 13, covering said boss and secured in place by the flanged tube 14, extending through said perforation, and wires adapted to connect said shell 5 and cap 13 with the lamp-filament, as described.

In witness whereof I have hereunto set my hand.

FREDERIC H. MANCHESTER.
